UNITED STATES PATENT OFFICE.

GEORGE DOUGLAS EDDINGTON, OF SALT LAKE CITY, UTAH, ASSIGNOR TO EDDINGTON LOUD SPEAKER INC., OF SALT LAKE CITY, UTAH, A CORPORATION OF UTAH.

LOUD SPEAKER.

Application filed November 25, 1924. Serial No. 752,196.

To all whom it may concern:

Be it known that I, GEORGE DOUGLAS EDDINGTON, a citizen of the United States, residing at Salt Lake City, in the county of Salt Lake and State of Utah, have invented certain new and useful Improvements in Loud Speakers, of which the following is a specification.

This invention relates to improvements in sound reproducing devices, operated electrically, and particularly to an electrically operated loud speaker adapted for use with radio receiving sets.

An object of the invention is to provide a loud speaker, which will produce a greater volume of sound, by utilizing both current fluctuations for operating means to produce sound waves.

Another object of the invention resides in providing a loud speaker having a pair of sound reproducing diaphragms between which is interposed electric means operable through fluctuations in the current in said electric means for producing fluctuations in the sound producing means in a manner that the sound producing means will utilize all of the fluctuations of the current in the electrical means.

A further object of the invention resides in providing a loud speaker including a pair of permanent magnets mounted at opposite ends of an electromagnet having an armature extending between the poles of said permanent magnet, and extending through the windings of the electromagnet, and operable by fluctuations of current in said electromagnet, to produce an operating movement thereof, and connections between said armature and a pair of diaphragms for utilizing the oscillations in each direction for operating respective diaphragms to reproduce sound waves corresponding with said oscillations.

The invention also includes other objects and improvements in the details of construction and arrangement of parts which are more particularly pointed out in the following detailed description and claims, directed to a preferred form of the invention, it being understood, however, that various changes in the details of construction, and arrangement of parts may be made, without departing from the spirit and scope of the invention as described and claimed herein.

In the drawing, forming part of this application:

Figure 1 is a plan view, showing portions broken away, and in section, of the improved loud speaker.

Figure 2 is a sectional view, taken on the line 2--2 of Figure 1, the casing being omitted.

Figure 3 is a horizontal sectional view, taken on the line 3--3 of Figure 2.

Figure 4 is a vertical sectional view, through the electromagnet, showing the details of construction of the armature, and the mounting therefor.

1 indicates a cabinet which is shown in dotted lines, having an open front, closed by hinged doors 2, and in which is mounted a casing 3, formed of mating sections, as illustrated in Figure 1, and provided with axially aligned openings 4, in each section, for receiving the reduced ends 5 of a pair of amplifying horns 6, having the mouths 9 in adjacent relation, and co-extensive conjointly with the open front of said cabinet. The casing section 3 has the inner ends of the openings 4 threaded for receiving the threaded extensions 7 of the diaphragm cup 8 having removable cover sections 9, to permit the insertion or removal of the diaphragm 10, into their proper positions within the diaphragm cups 8.

The central portions of the covers 9 are provided with openings 11, and a rod 12 extends axially through the openings of both of the covers 9, and is connected at its end portions to the central portions of the diaphragms 10, in order that both of the diaphragms will vibrate synchronously.

The faces of the caps 9 are arranged in opposed relation, and are spaced apart in a manner as shown in Figure 1. An electromagnet 13 is mounted with its axis parallel to the faces of the covers 9, and between said cover plates, the end portions abutting the poles of a pair of ring shaped permanent magnets 14 and 15 respectively. U-shaped brackets 16 have the bridle portions secured to the cap 9, while the leg portions are secured to the magnets 14 and 15 by suitable screws 17, in order that the electromagnet and the permanent magnet may be permanently associated and mounted between the caps 9.

The core 18 of the electromagnet 13 is formed of brass or other non-magnetic

metal, and is formed with an elongated opening 19 extended axially therethrough, for receiving the armature plate 20, which is hingedly mounted in its central portion 5 on the pin 21 carried in the central portion of the elongated opening 19 of the core 18. In assembled relation, this armature plate is arranged normally at right angles to the rod 12 connecting the diaphragms 10, 10 and is provided with a projection 22, from the central portion of one end, adapted to be pivotally connected to said rod 12, in order that the oscillation of the armature plate will effect an oscillation or vibration 15 of the diaphragms.

Each permanent magnet 14 and 15 respectively, is formed of a split ring member, in which the opposite portions are cut away at respectively opposite sides, as indicated at 23, to provide overlapped ends 24, which are spaced from each other, as indicated at 25. These overlapped ends form the poles to the magnet, in order that the magnetic flow from pole to pole will be 25 in a direction parallel with the axis of the ring. These rings are mounted at opposite ends of the electromagnet 13 in a manner that the similar poles of each electromagnet 14 and 15 respectively are arranged 30 at opposite sides of the armature plate 20, so that the permanent magnets will normally operate the armature plate in one direction, to tension the diaphragm 10. Suitable terminals 26 are mounted at one 35 end of the bracket 16, under the screws 17, and suitably insulated therefrom, and receive the connections at the opposite ends of the coil 13, in order that the same may be interposed in the output circuit of a 40 receiving set or other type of electrically operated sound amplifying means, in order that the sounds in said output circuit may be reproduced, and further amplified.

The energization of the electromagnet 45 13 will set up a magnetic field, which will affect the fields of the magnets 14 and 15 respectively, and thereby effect the operation of the armature 20, and under the variations of this magnet field of the electromagnet 13, corresponding to the variations in the output circuit of the amplifying device, (not shown), for causing oscillation 50 of the armature plate 20, in accordance with these variations in the magnetic field, which 55 will operate the diaphragms 10, for reproducing the sounds, according to the fluctuations of the magnet field, so that both portions of the fluctuations on the armature plate will be utilized in the production of 60 sound waves directed outwardly through the amplifying horns 6, so that a maximum sound reproduction for the amount of current in circuit with the magnet 13 will result.

65 In addition, the use of two permanent

magnets for actuating the armature plate 20 and the use of a substantially wide armature plate to be acted on by said magnet with the electromagnets disposed between the permanent magnets for varying the fluctuations of each, to effect an operation of the armature plate will result in the production of the maximum strength of sound reproduction in the diaphragms 10, by the efficient operation of the armature plate at 75 both sides of the pivot or hinge 21, in order that a strong and yet clear sound reproduction may be had, utilizing the vibration or oscillation of the armature plate, in each direction. 80

What is claimed is:

1. A device of the class described comprising a pair of spaced parallel diaphragms, a rod connecting the central portions of said diaphragms, an armature connected at one end to said rod and hingedly mounted at its central portion for oscillating movement, a pair of independent ring shaped permanent magnets arranged with the poles in opposed relation and operative 90 relation with opposite ends of the armature plate, and an electromagnet arranged between said permanent magnets in close proximity to the poles thereof energizable for varying the magnetic effect of both permanent magnets on the armature plate, for operating the armature plate and the diaphragm in accordance with the current variations of the electromagnet. 95

2. A device of the class described comprising a pair of spaced parallel diaphragms, means connecting said diaphragms for simultaneous operation, an armature hingedly mounted in its central portion for oscillating movement, and connected with the means connecting the diaphragm for oscillating said means in an oscillating movement of the armature, permanent magnets arranged in operative relation with the opposite ends of the armature, each permanent magnet operating the armature in a like manner, and an electromagnet positioned between the poles of the permanent magnet and adapted for connection with an output circuit of an electrically operated sound amplifying device, for varying the fields of said permanent magnet, according to the fluctuations of current in circuit, and effecting a corresponding operation of the armatures and diaphragms in accordance with the fields fluctuation. 110

3. A device of the class described comprising a casing formed with mating sections, a pair of diaphragm cups mounted in opposed relation in said casing having sound outlets therethrough, horns mounted in the sound outlet formed in the casing section, sound reproducing diaphragms mounted in said diaphragm cups, a connect- 125 130

ing rod having the ends secured to the central portions of said diaphragms, an electromagnet mounted between the diaphragms and having an elongated opening extending 5 axially through the central portion thereof, an armature plate hingedly mounted in its central portion in said elongated opening and connected with said connecting rod, for operating the diaphragms in the oscillation of the armature plate, and a pair of 10 permanent ring shaped magnets arranged at opposite sides of said electromagnet, for effecting a similar operation on the armature, said electromagnet adapted to be con-

nected with the output circuit of an electrically operated sound reproducing means 15 for varying the magnetic field operating said armature plate to cause an oscillation of the same, the sound diaphragm reproducing the sound according to the oscillation 20 of the armature plate, each sound diaphragm utilizing the opposite portions of an oscillation in the reproduction of a sound.

In testimony whereof I affix my signature. 25

GEORGE DOUGLAS EDDINGTON.
